TOY WITH MAGNETICALLY OPERATED
STRIKING MEMBERS

Charles R. Luchsinger, Glen Cove, N.Y., assignor to The Luchland Company, Newfoundland, N.J., a partnership
Filed May 19, 1965, Ser. No. 457,040
1 Claim. (Cl. 273—108)

ABSTRACT OF THE DISCLOSURE

Oval shaped pellets weighted at one end and propelled into apertured targets in a game board by a striking member. The striking member has a rounded magnetized base and outstretched wings. These wings impact against the pellets. The striking member is moved by a magnetic control stick which interacts with the magnets of the striking member.

This invention relates to a magnetically operated toy comprising pellets and magnetic striking means therefor together with magnetic actuating members for controlling the operation of the striking members.

It is one of the objects of the present invention to provide a toy in which skill of operation is a factor in using the toy to play a game but in which a certain erratic operation of the components produces spontaneous, anomalous results that greatly enhance the enjoyment of the toy and at the same time provide an additional requirement for skill on the part of the players. Further objects will become apparent hereinafter.

The toy with which the present invention is concerned comprises basically a playing board or surface with one or more target areas and one or more pellets disposed about the surface of the board. Also disposed on the board is at least one striking member which has a permanent magnet as one of its component parts and one or more arms with which the pellet or pellets may be struck. Each striking member is controlled by at least one control member operated by at least one of the players and placed beneath the board. The control members also have magnets that provide fields interacting with the magnetic field of the striking members so that motion of the control members determine more or less precisely the way that the striking members will move. In general, the object of the game is for each player to move a control member beneath the board so as to control one of the striking members and thereby hit or push one or more of the pellets to a predetermined target area. Certain modifications of the game will be spelled out in detail hereinafter.

The invention will be described in connection with the drawing in which:

FIG. 1 is a perspective view of one embodiment of the toy or game of this invention;

FIG. 2 is a cross-sectional view of the toy or game of FIG. 1.

The toy of FIG. 1 includes a playing board 11 having a raised rim 12 and corner legs 13 to hold the play board 11 off of a surface, such as a table or the floor or any other suitable support. On the board 11 are two striking members 14 and 14a, each comprising a rounded base 16 and 16a and a figure, which in the present embodiment is in the form of a chicken 17 and 17a with outstretched wings 18 and 19 for the member 14 and 18a and 19a for the member 14a. The striking members 14 and 14a also include permanent magnets which are not visible in FIG. 1.

Several pellets 21-24 are disposed about the surface

2

of the board 11, and in the present embodiment these pellets are oval-shaped to represent eggs; although for other embodiments of the game different forms of pellets may be used. Preferably these pellets are weighted at one end so as to be heavy in an asymmetrical manner and thereby increase the erratic courses to be folded when these pellets are struck by the outstretched wings, or extensions, 18 and 19 of the member 14 or the wings 18a and 19a of the member 14a.

Three target areas are shown on the board 11 in the form of three apertures 26-28. In the present embodiment these apertures represent nests to receive the pellets 21-24. If desired, the target apertures 26-28 may be numbered or their rims colored to correspond to certain of the pellets 21-24, and the striking members 14 and 14a may also be correspondingly colored. However, it is not essential to the basic invention that any particular coloring relation be followed.

The striking members 14 and 14a are moved about by control members 29 and 31 of which only the handles are visible in FIG. 1. These control members include magnets that interact with the magnets in the striking members 14 and 14a to move the latter about the surface of the board 11 and to cause the wings 18, 19 and 18a, 19a to push or strike the pellets 21-24 and eventually to direct these pellets into the target apertures 26-28.

FIG. 2 is a cross-sectional view of the toy of FIG. 1 and better illustrates the arrangement and relationship of the control member 29 and the striking member 14a. As may be seen, the base 16a of the striking member 14a is hemispherical in shape and is weighted down to be sure that it remains in contact with the surface of the board 11 and that the respective striking members 14 and 14a do not topple over. Part of the weight may be furnished by a permanent magnet of alnico or one of the ferrite permanent magnetic materials and indicated by reference character 32a.

The control member 29 includes a permanent magnet 33 the magnetic field of which coacts with the magnetic field of the magnet 32a either to repel or to retract the striking member 14a and thus to permit the striking member to be guided, at least crudely, around the surface of the board 11 by means of the control member 29. At the same time the interaction of these magnetic fields provides means for causing the extensions 18a and 19a to strike the pellets of which only the pellets 23 and 24 are shown.

If the game is used as a competitive game in which two or more players attempt to cause designated pellets to drop into designated aperture targets of which only the apertures 26 and 28 are shown in this figure, the striking members, of which there were usually but one for each player, may be guided by the respective control members of the players either to cause that player's pellet to fall into its designated target apertures or to force an opponent's pellet to be diverted away from its designated target area. The game may be played with many variations of the rules to provide either simpler or more complex games so as to adjust the degree of difficulty to the skill of those playing and thereby make the game suitable for people of different skill or age levels.

While the invention has been described in terms of a specific embodiment it will be recognized by those skilled in the art that modifications may be made therein within the scope of the claim.

What is claimed is:

1. A toy comprising: a playing board having a plurality of target areas and a ridge around the perimetre of said board; a plurality of oval-shaped pellets disposable on said
